United States Patent Office.

F. W. HENSON, OF PHILADELPHIA, PENNSYLVANIA, ASSIGNOR TO HIMSELF AND T. S. HENSON, OF SAME PLACE.

Design No. 3,579, dated July 13, 1869.

DESIGN FOR A SCARF-PATTERN.

The Schedule referred to in these Letters Patent and making part of the same.

To all whom it may concern:

Be it known that I, F. W. HENSON, of Philadelphia, county of Philadelphia, State of Pennsylvania, have originated a new Design for Scarfs; and I do hereby declare that the accompanying drawing, and following explanation thereof, form a full, clear, and exact description of the said design.

In the drawing—

Figures 1 and 2 represent sufficient of a scarf to illustrate my design, which consists of the opposite borders, A A, and central pattern, B, each border consisting of stripes, a a, and figures, b b, and the central portion consisting of a number of stripes of different colors, or different shades of color.

Irrespective of the colors employed,

I claim the design for scarfs substantially as described, and as illustrated in and by the accompanying drawing.

In testimony whereof, I have signed my name to this specification, in the presence of two subscribing witnesses.

Witnesses:

JOHN WHITE,
LOUIS BOSWELL.
